MUFFLER MANIFOLD

Application filed May 29, 1928. Serial No. 281,504.

The present invention relates to manifolds for internal combustion engines and has to do particularly with those manifolds which are designed to muffle exhaust explosions and reduce the resulting noise in the exhaust line as well as that transmitted through the metallic parts of the engine and associated mechanism.

The manifold embodying the present invention is formed with air pockets which are designed to set up wave impulses which destroy the direct impulses from the exhaust gases. These destructive impulses are produced by reflecting direct impulses from the exhaust gases from the air pocket and combining the reflected waves with the direct waves in such manner that the vibrations of one destroy those of the other. It will be understood, of course, that the length of the pocket must be sufficient to cause the path of the reflected impulses to be such that the nodes of the reflected gases will be out of phase with those of the direct gases.

It is further proposed to form the manifold with suitable baffling means to cause the path of all of the exhaust gases within the manifold to be restricted in a manner to cause the wave impulses from the several exhausts to destroy one another to as great an extent as possible.

The manifold embodying the present invention is formed of generally tubular shape and provided with air pockets at either end. The inlet ports are situated so that the gases which they introduce into the manifold are baffled before reaching the exhaust port. The specific form and assembly of elements will be understood more fully in connection with the accompanying drawings, wherein:

Figure 1 is a plan view, partly broken away and in section, showing a manifold constructed in accordance with the present invention.

Figure 2 is a side elevation, partly broken

away and in section, showing the muffler manifold of Figure 1.

Referring to the above figures, *a* indicates the cylinders of an internal combustion engine. To the exhaust ports of these cylinders, inlet conduits *b* are connected. These conduits are formed with a manifold *c* which is of a generally tubular form and very large. In the present embodiment, the manifold has been shown as constructed in two sections and joined together as at *c'*. The exhaust port for the manifold is shown at *d* and may be located at any desirable point in its length, subject only to the structural limitations imposed by the baffle which will be described later.

At either end of the manifold, a cap-shaped closure *e* has been provided. Threaded arms *c*² are secured to the manifold and receive nuts *c*³ which serve to adjust the position of the cap *e* with respect to the manifold *c*. The cap *e* is provided with suitable flanges *e'* against which the nuts *c*³ engage and adjusting of the nuts with respect to the threaded arms *c*² causes the length of the air pocket to be varied. It will be obvious, that having once ascertained the proper depth of air pocket, the manifold and caps can be constructed as a unit, the latter being formed with the former.

Extending from the left end of the manifold, and for a portion of its length, is a horizontal baffle plate *f* which is shown as perforated along its horizontal portion as indicated at *f'*. These perforations permit a limited quantity of exhaust gases to pass through the plate and at the same time preserve its character as a baffle for the gases. The baffle plate terminates in an upwardly extending tongue shaped extension *f*², the edges of which are formed to provide about a quarter of an inch clearance between the extension and the wall of the manifold. This clearance extends around the entire edge of the exten-

sion and serves as a baffle for the gases in the outer end of the manifold. It will be apparent that the gases passing through the manifold will be baffled by the plate f or its extension f^2 before they pass out through the exhaust port d . The combined areas of the holes in the plate, as well as the clearance between the extension and the manifold, are made more than sufficient to handle the 10 gases coming from the three rear cylinders and the three forward cylinders, respectively. It is quite apparent that the character of these elements may be varied to accommodate the individual requirements of various 15 designs.

The noise emanating from the exhaust impulses, particularly at higher engine speeds, is greatly reduced by reason of the destructive wave impulses reflected by the air 20 pockets formed by the caps at either end of the manifold as well as the baffling of the gases by the plate f and extension f^2 . The restriction of the flow of gases by this plate and extension causes them to travel by various paths and thus use up some of the 25 energy which causes noise as well as tend to destroy the wave impulses of the gases in conflicting paths.

As an added feature of the invention it has 30 been discovered by experience that the above manifold has resulted in a lower temperature under the exhaust valves. This temperature has been lowered from 300 to 400° Fahrenheit and the engine performance has 35 been improved materially. The lower temperature enables a higher compression to be obtained with a correspondingly greater development of power from the engine. As an additional advantage, the valves have a 40 greater life and the necessity of regrinding them in considerably reduced.

Although the invention has been described with respect to the accompanying drawings, it is not to be limited save as defined in the 45 appended claims.

We claim as our invention:

1. A muffler manifold having an exhaust port and a plurality of inlet ports, a tubular chamber, a pocket formed at one end of the 50 chamber, a single perforated baffle forming a longitudinal partition for a portion of the length of the chamber, and a bent extension on the baffle forming, with the walls of the chamber, a restricted portion through which 55 part of the exhaust gases pass.

2. A muffler manifold having an exhaust port and a plurality of inlet ports, a tubular chamber, and a single, longitudinally extending baffle in the chamber from one end to the 60 middle thereof.

3. A muffler manifold having an exhaust port and a plurality of inlet ports, a tubular chamber, and a single, longitudinally extending baffle in the chamber from one end to 65 the middle thereof and substantially parallel

to and in front of the face of the exhaust port.

4. A muffler manifold having an exhaust port and a plurality of inlet ports, a tubular chamber, a single longitudinally extending 70 perforated baffle in the chamber, and a bent extension on the baffle terminating short of and cooperating with the sides of the chamber to form a restricted passage between the extension and sides to baffle the gases.

This specification signed this 17th day of May A. D. 1928.
